(57) **CLAIM**

The ornamental design for a tire, as shown and described.

DESCRIPTION

FIG. 1 is a first side view of the tire;
 FIG. 2 is a front view of the tire, the back view of the tire
 being identical thereto;
 FIG. 3 is a second side view of the tire, opposite the first side
 of FIG. 1; and,
 FIG. 4 is a perspective view of the tire.

1 Claim, 4 Drawing Sheets(56)
